VACUUM TUBE ELECTRONIC SWITCH

Burns Conley, United States Army,
Wevaco, W. Va.

Application April 11, 1945, Serial No. 587,822

4 Claims. (Cl. 250—27.5)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to electronic devices and more particularly to a vacuum tube electronic switch having a movable grid.

Heretofore, the small output currents of devices such as photo-electric cells and thermocouples had to be amplified before such currents could be applied to anything but a sensitive meter.

It is an object of this invention to provide an electronic switch or relay capable of producing electrical impulses of a much greater magnitude than the electrical impulses actuating the device.

It is another object of this invention to provide a thermionic device for use in connection with electrical apparatus of the type that is capable of producing only an extremely weak current, such as photocells, thermocouples, etc.

According to my invention a thermionic switch is provided with a cathode, a plurality of anodes positioned to receive a flow of electrons from said cathode, a control electrode mounted for rotation relative to the cathode and arranged to control the electron flow from the cathode to the respective anodes, and a D'Arsonval type of meter having an armature upon which the control grid is mounted, the entire thermionic device being inclosed in an evacuated envelope.

Further objects and advantages of this invention will become apparent from a consideration of the following specification together with the accompanying drawings in which:

Figure 1 is a perspective view of a thermionic device embodying the invention, viewed from one end.

Figure 2 is a partially cut-away perspective view of the embodiment shown in Figure 1, viewed from the other end, with base removed.

Figure 3a is a schematic view of the control electrode in the "off," or resting position.

Figure 3b is a schematic view of the control electrode in one operative position, whereby current flows in both anodes.

Figure 3c is a schematic view of the control electrode in another operative position, so that current flows in both anodes.

Figure 3d is a schematic view of the control electrode in the full "on" position.

Figure 4a is a perspective view of a modified form of control electrode that may be utilized in my invention.

2

Figure 4b is an end view of the modified form of control electrode illustrated in Figure 4a.

Figure 5a is a schematic view of the modified form of control electrode in the "off" or resting position,

Figure 5b is a schematic view of the modified form of control electrode in position so that current flows in both anodes.

Figure 5c is a schematic view of the modified form of control electrode in such position that the direction of anode current is reversed.

Referring to Figures 1 and 2 it is seen that the reference numeral 10 refers to an evacuated envelope having a base 11 and contact prongs 12.

15 A D'Arsonval type meter 13 is situated in an end of the evacuated glass envelope 10 opposite from the base 11. The D'Arsonval meter 13 is of the conventional type having permanent magnet poles 14, 15, and a rectangular armature coil 16

20 pivotally mounted in such fashion as to permit rotation. The rotatable armature coil 16 is mounted on low-friction bearings (not shown)

25 and is biased to zero position by the usual spring 17.

25 A glass sealing stem 18 in the base of the tube supports a cylindrical cathode 19 of the indirectly heated type. Two oppositely and pref-

30 erably symmetrically situated anodes 20 and 21 are supported by mounting rods 22 set in the sealing stem 18. A U-shaped control electrode or grid 23 made of a single piece of heat-re-

35 sistant wire having two coplanar legs or prongs 24 and 25 is rigidly fastened at its lower end 26 to a meter armature shaft 27 that is perpen-

35 dicularly affixed to the meter armature coil 16.

The control electrode 23 is formed and mounted in such fashion that the two sides or prongs 24,

35 25 extend alongside the entire length of the cathode 19. The two prongs 24 and 25 are so

40 situated that they are positioned 180° apart on a circle of which the cathode 19 is the center.

The two sides or prongs 24, 25 of the control electrode 23 rotate around the outside of the cathode 19 when the armature coil 16 is moved

45 by current flowing through it.

As previously stated, the anode portion of the device is divided into two parts, 20 and 21, with each half electrically separate and situated dia-

50 metrically opposite each other and electronically

50 surrounding about a third of the cathode 19. The anodes 20 and 21 may be connected in parallel

55 or any other manner desired.

It is thus seen that the application of an ex-

55 tremely weak current such as the output of a photoelectric cell or thermocouple to the arma-

ture coil 16 will cause the coil and the control electrode 23 to rotate. The rotation of the control electrode 23 will cause a change in the amount of electron flow from the cathode 19 to the anodes 20 and 21, with a resulting change in the anode current.

Referring to Figure 3a, there is disclosed in schematic fashion the normal resting or "off" position of the control grid 23. The control electrode or grid 23 is in such position that it prevents substantially any electrons from reaching either anode 20 or 21 with the result that no current flows in either anode circuit. The control electrode 23 should be biased with the proper potential to have a cut-off value when in this position.

In Figure 3b the control electrode has been moved slightly clockwise, the result being that some electrons which are not affected by the grid reach the anodes 20 and 21 and cause a small current flow in both anode sections.

In Figure 3c the control electrode or grid 23 has rotated still more in a clockwise direction with the result that a larger anode current will flow than in the previous illustrations.

In Figure 3d the full "on" position is reached where the control electrode or grid 23 does not act on the sides of the cathode that face the anodes 20 and 21, the result being that there is maximum current flow in both anode sections.

When no current is flowing through the meter 13, it is brought back to the "off" or normal position by the meter spring 17 which swings the control electrode 23 between the cathode 19 and the anodes 20 and 21, thus cutting off the current flow in the tube. The normal resting position of the control electrode 23 may be made such that current will flow when no signal is applied by changing the position of the two anodes to a 90° setting from their original position. By changing the bias on the control electrode or grid the plate current can be made to vary in proportion. With a smaller bias the cut-off point would be reached more slowly than with a high one even with the same speed of control electrode movement. With a higher negative bias the cut-off position would be reached much quicker. The bias on the grid would also determine how far the control electrode 23 would have to be rotated by the meter to have a cut-off value, but the maximum distance in any case would be 90°.

Referring to Figure 4, there is disclosed a modified type of control electrode or grid. The prongs or tines 24 and 25 are placed on the meter shaft 27 in such manner that the prongs are at an angle of 90° to each other, rather than 180° to each other as shown in Figures 1 and 2. With this arrangement, the anode currents will work in opposition to each other, that is, while the current in one anode is approaching a maximum value, the current in the other anode will be approaching a minimum value and vice versa. The modified control electrode, as illustrated in Figure 4, is shown in various operative positions in Figures 5a, 5b, and 5c.

In Figure 5a, the control electrode or grid is shown in the normal resting or "off" position with the result that substantially all of the electrons emitted from the cathode flow to only the anode 20 with no current flowing in the other anode 21.

In Figure 5b the control electrode or grid has been moved counter-clockwise with the result that part of the electron flow reaches each anode and a small amount of current flows in each anode circuit.

In Figure 5c the control electrode has been rotated still more in a counter-clockwise direction so that substantially all of the electron flow from the cathode is directed upon the anode 21 with no current flowing in the anode 20.

Although I have illustrated an embodiment of my invention in which two anodes are used, it is obvious that a tube of this type may be constructed with any number of anodes surrounding the cathode.

My electronic switch may be utilized in various ways. For example, relays may be placed in the anode circuits so that the extremely weak actuating currents fed into my device will operate them without utilizing any amplifying means. Or, the external anode circuits of my device may include any type of electrical indicating means that would not be capable of being directly operated by the extremely weak current available from a device such as a photoelectric cell or thermocouple.

Obviously the present invention is not restricted to the particular embodiments or uses shown herein and described, the scope of the invention being defined in the appended claims.

I claim:

1. An electrical switch comprising a sealed evacuated envelope inclosing a central cathode, a plurality of anodes radially spaced from said cathode, a fork-like control electrode having two parallel prongs, each prong extending lengthwise of said cathode, and electrical means positioned within said envelope for rotating said control electrode, said electrical means comprising a permanent magnet and a rotatable armature both coaxial with said cathode.

2. The structure according to claim 1 in which the two parallel prongs of said fork-like control electrode are positioned 90 degrees apart on a circle concentric with said cathode.

3. An electrical switch comprising a sealed elongated evacuated envelope inclosing an elongated central coaxial cathode, a plurality of anodes radially spaced from said cathode, a fork-like control electrode extending the length of said cathode and mounted for rotation between the cathode and anodes; and electrical means for rotating said control electrode positioned within said envelope including a permanent magnet and a rotatable armature, both coaxial with said cathode.

4. The structure according to claim 3 in which the two parallel prongs of said fork-like control electrode are positioned 90° apart on a circle concentric with said cathode.

BURNS CONLEY.
